INDUSTRIAL GAS-FIRED AIR HEATER

James A. Harrison, Southfield Township,
Oakland County, Mich.

Application March 6, 1947, Serial No. 732,746

14 Claims. (Cl. 263—19)

1
This invention relates to industrial heating equipment and particularly to gas-fired heating apparatus for supplying heated air to process ovens or furnaces or for supplying tempered air to factory spaces in order to make up the air which is exhausted by ventilating systems.

Heretofore, industrial air heaters of this character have been of two types, namely either pull-through or blow-through. In the pull-through type, the air heater is installed on the inlet side of the system's air moving fan, and in the blow-through type, when used, the air heater is installed on the discharge side of the fan.

Pull-through type heaters have been equipped with atmospheric type gas burners which for temperature control purposes have turn-down ratios limited approximately three-to-one. Blow-through type heaters have been equipped with blast type gas burner equipment requiring a combustion air blower to deliver the primary air at from 16 ounces to 32 ounces pressure. The turn-down ratio of this blow-through type is limited to from four-to-one to six-to-one. Due to the limited turn-down ratio of these two types of air heaters, it has been necessary that they be manufactured with a great number of gas burner sizes in order to answer the specific capacity needs and still have turn-down available for the control of the temperature of the air being heated. Likewise it has been necessary that the size of the air heater be quite accurately selected due to the limited range in turn-down.

An important object of this invention is to provide an improved air heater which is relatively inexpensive to manufacture and install, is highly efficient and more economical in operation, and has a considerably higher turn-down ratio than heretofore which enables the delivered air temperature to be accurately set and maintained.

Another important object of this invention is to provide an improved air heater construction including novel means for economically and efficiently mixing the air and gas to form a combustible mixture, and burning this combustible mixture to heat the air forced through the combustion zone, with burners interchangeable for wide increases or decreases in heater capacity.

A further important object of the invention is to provide the air heater with burners which will efficiently operate when air is blown through the air heater by the system's fan without the necessity of using a separate costly combustion air-blower and still have a turn-down ratio far in excess of that available with existing air heaters.

2
A further important object of this invention is to provide an air heater that can be employed in either a blow-through or pull-through type of system without change other than adjustment.

5 A further important object of the invention is to provide an air heater which has adjustable air passages so that not only the total passage can be adjusted for air handling capacity but the passages can be individually adjusted to distribute the air equally on both sides of the flames of combustion.

10 A further important object of this invention is to provide an air heater with adjustable air passages so that the passages can be partly closed when the air heater is first lighted and the air passing therethrough is cold and heavy thus eliminating the necessity of employing an oversize motor for operating the circulatory air fan.

15 A still further important object of the invention is to provide a novel control mechanism for the apparatus which provides a large turn-down ratio and enables the apparatus to be adjusted within a fine degree of accuracy to provide the desired temperature in the chamber, oven or furnace into which the heated air is directed.

Other objects, advantages and meritorious features will become more fully apparent from the following specification, appended claims and accompanying drawings wherein:

20 Fig. 1 is a schematic view of a system embodying the features of the invention showing the manner of heating and circulating the air through a treatment chamber.

25 Fig. 2 is a cross sectional view through the air heating apparatus taken along line 2—2 of Fig. 1.

Fig. 3 is a longitudinal sectional view of the air heating apparatus taken along line 3—3 of Fig. 2.

30 Fig. 4 is a schematic view showing the manner of controlling and delivering gas to the heating apparatus, and

Fig. 5 is a graph illustrating the operation of the invention.

The invention may be embodied in various forms and is herein illustrated as applied to a heat treatment oven or chamber from which air is drawn and heated and returned to heat the chamber. Referring to Fig. 1, the heat treatment chamber is generally indicated at 10 and is provided with an air inlet 12 at one end and an exhaust stack 14 at the other end. Both the inlet and exhaust openings may be varied in size by suitable valve control means. A circulatory system is provided for removing air from one portion of the chamber, heating it and returning

the heated air to another portion of the chamber. In operation, the inlet and exhaust openings are usually adjusted so that approximately 75% or more of the air is circulated through the system, the balance being introduced and discharged through the inlet and outlet openings.

The air circulatory system comprises a circular duct 16 generally mounted outside of the chamber and provided with a return air intake 18 entering the upper area of the chamber to draw air therefrom. The opposite discharge end of the duct 16 is provided with an air supply section 20, entering another portion of the chamber, and constructed with a horizontal distributary section 22 having a series of discharge openings 24 for distributing the heated air over the lower area of the chamber as shown by the arrows in Fig. 1.

Although the duct 10 and the heating apparatus therein may be disposed inside the chamber, it is preferred for accessibility to locate the duct 16 outside the chamber over the top as shown or along either side wall. The duct is provided with means in the form of an air blower or fan 26 for drawing air through the intake 18 and forcing it through the balance of the system. Provided in the duct 16 is a slightly reduced circular section 28 in which the air heater is located. In the illustrated embodiment of the invention, the air blower 26 is located on the inlet side of the air heater and the system typifies a blow-through type of apparatus. It may, however, be located on the outlet side of the casing and pull air therethrough as in the pull-through types of apparatus. In the preferred construction, the air blower functions to direct the air under pressure of one to four inches of water column.

The reduced section 28 is in the form of a hollow casing in which is contained the air heater. The air heater includes a plurality of gas burner units of similar construction arranged in circularly spaced relation around the axis of the casing as shown in Figs. 2 and 3. Each burner unit comprises a Venturi tube 30 having the constricted portion of its passage preferably nearer the inlet end than the outlet end. Air is forced by the blower 26 through the entire length of each venturi, traveling at a greater rate of speed through the constricted area than any other portion of the venturi. At approximately the minimum diameter of the venturi, gas is admitted and mixed with the air. The gas is delivered separately to each burner unit by a tube or pipe 32 preferably formed of copper. Each tube 32 opens into the constricted passage of the venturi of its respective burner unit as shown at 34. Preferably, the discharge end section of the gas delivery pipe is wound one or more turns around the Venturi tube as shown at 35 to thereby preheat the gas therein before it discharges into the Venturi tube. The purpose of this is to preheat the raw gas before admission into the burner units to thereby proportionately expand the volume of gas delivered as the temperature of the air increases. Air forced through each Venturi tube picks up the gas admitted thereinto and carries it to the discharge end while it mixes therewith. At the discharge end of the Venturi tubes, the air and gas flows therefrom in a combustible stream and in ignited condition forms the flame jets generally indicated at 36.

As previously mentioned, the Venturi tubes are arranged in circularly spaced relation around the axis of the casing. The series of Venturi tubes are mounted between two substantially

coaxial sleeves 38 and 40 of unequal radii. The outer sleeve 38 is cylindrical and is less than the length of the casing 28 and preferably located closer to the inlet side of the casing than the outlet side thereof. The inner sleeve 40 is mounted substantially within the outer sleeve and is provided with a conical section 42 which flares slightly outwardly toward the flame jet area and then is shaped with a short cylindrical section 44 at its discharge end. Both the sleeves project a slight distance beyond the discharge end of the Venturi tubes as shown in Fig. 2. The inner sleeve 40 is opened at both ends and forms a relatively large passage for the flow of air through the duct system. The outer sleeve 38 is spaced inwardly from the wall of the casing 28 and forms an annular passage 45 therearound for the flow of controlled amounts of air therethrough.

On the axis of the casing is a conical shaped member or plug 46, preferably diamond shaped in longitudinal cross section, which is mounted for longitudinal adjustable movement. The plug 46 is mounted within a fixed subsidiary sleeve 48 supported by brackets or otherwise centrally within the casing. The sleeve is preferably provided with tapering conical end sections 50-50 which preferably converge toward the axis of the casing at the same angle of inclination as the conical sides of the plug. The plug is fixed on an axially extending rod 52 which is mounted by spaced supports 54-54 for longitudinal movement. One end section of the rod is provided with rack teeth 56 meshing with a pinion 58 fixed on a transversely extending control shaft 60. The latter is provided with any suitable means, such as the hand wheel 62, for effecting rotation of the shaft, which will advance or retract the plug relative to the sleeve 48 to vary the air flow as will be more particularly described hereinafter. The maximum diameter of the plug bears such a relation to the sizes of the end openings of the sleeve 48 that when adjusted to the extreme positions of its longitudinal movement it substantially closes off the flow of air through the sleeve. Movement of the plug toward closing position at either end of the sleeve will build up a pressure differential between inlet and outlet sides of the air heater. The pressure differential or drop should be greater than $\frac{1}{4}$ inch water column to prevent flash back in the burner tubes 30.

The annular passage 45 formed between the casing 28 and the sleeve 38 allows a flow of a controlled amount of air from the inlet side to the outlet side of the heater. This is preferably accomplished by providing an annular plate 64 on the inlet side having a series of equally spaced apart openings or ports 66 circularly arranged around the axis of the casing 28 and concentric thereto. These openings are spaced apart from one another approximately their circumferential dimensions as shown in Fig. 2. Overlying the plate 64 is a second annular plate 68 which is substantially the same size as the former and similarly provided with a series of openings or ports corresponding in size to the openings 66. This second annular plate is mounted for rotatable adjustment relative to the first plate from one extreme position in which the openings of the two plates are in complete registration to the other extreme position in which the openings are completely out of registration and no air will flow therethrough. The plate 68 may be adjusted to any intermediate position between these extreme

positions and thereby regulate the amount of air flowing through the annular passage 45.

The rotatable plate may be either manually or automatically adjusted and is herein shown as automatically adjustable in response to the temperature changes in the treatment chamber. As shown in Fig. 2 an adjusting rod 70 is provided for this purpose which extends substantially tangentially through an opening 72 in the casing 28 and has one end pivotally connected as at 74 to the annular plate 68. The opposite end is connected by linkage, such as that shown at 76 in Fig. 1, to an electric motor 78 or other suitable operating device. The latter is provided with a thermal responsive control element 80 projecting into the treatment chamber or other heated space and as is conventional practice the control element in response to temperature changes opens and closes electrical switches and causes the motor to turn over in one direction or the other and either pull or push the linkage system and rod 70 to vary the overlapping relationship of the openings or ports in the two annular plates 64 and 68.

The air passing through the Venturi tubes 30 forms the primary air of the combustible mixture. The air passing through the annular passage 45 and the annular passages formed by the innermost pair of sleeves 40 and 48 forms the secondary air of the combustible mixture. By virtue of this arrangement, secondary air is supplied to both the outer and inner sides of the flames of combustion represented at 36 and an efficient burning operation results. Adjustment of the plug 46 and the size of the ports 66 will not only vary the air handling capacity of the heater but vary the distribution of the air so that if desired an equal amount of secondary air may be provided on both sides of the burning mixture issuing from the tubes 30.

Moreover, by adjusting the air handling capacity of the heater it is possible to reduce the amount of air flowing therethrough when the air is cold and increase the capacity progressively with the increase in temperature. The motor 78 and its thermal responsive control element are so related to the temperature in the treatment chamber that when the air therein is relatively cold, the size of the ports 66 are adjusted to approximately their minimum size to thereby reduce the volume of air passing through the heater unit. As the temperature of the air in the treatment chamber and in the duct system increases, the motor is controlled to open the ports 66 wider until at the maximum temperature for which the apparatus is set is attained at which time the ports will be opened approximately their widest extent. By virtue of such a control, it is possible to use a low horse power motor for the blower fan 26 because when the air passing therethrough is cold and heavy its volume is cut down, but as the air temperature increases and the air becomes lighter in weight the capacity of the heater increases proportionately.

The gas delivery tubes 32 which separately open into the burner tubes communicate with a common source of gas maintained at the desired pressure. Referring to Fig. 4, the gas delivery tubes represented by the lines 32 extend to a common control unit which is operable to progressively increase or decrease the number of lighted burners. The control unit comprises a circular housing 82 having a rotary valve member 84 therein. The latter is secured to a shaft 86 which is operatively coupled to a reversely op-

erated electric motor 88 of the type shown at 78. The motor 88 in turn is controlled by a thermal responsive control element 89 similar to 80 which extends into the treatment chamber or is in thermal relation to the air therein.

Each gas delivery line 32 has a separate inlet port opening into the housing 82 as indicated at 90. These openings or ports are located in one side wall 92 of the casing over which the valve member 84 sweeps. When the valve member overlies a port 90 it cuts off the delivery of gas to the line 32 communicating with this port. The ports 90 are arranged in a semi-circular series and the valve member is generally in the formation of a semi-circular segment adapted in one position, such as that shown in Fig. 4, to overlie and close all the ports with the exception of one port. The single exception is indicated at 94 and the valve member is cut away as at 96 in order that when the valve member is in the maximum closed position shown in Fig. 4 the single port 94 remains open for the delivery of gas to burner with which it is connected. This burner will serve as the pilot and be continuously lighted. Suitable stop means may be provided on the valve member or the shaft 86 limiting the rotation between the maximum closed position shown in Fig. 4 and the maximum open position where all the ports 90 are open for feeding gas to all the burners, or the motor 88 may be so controlled as to limit the rotation between these two limits. In addition, if desired, individual manually controllable valves may be installed in each gas delivery line 32. Such valves are represented at 98 in Fig. 4.

Any suitable detent means may be provided for causing the valve member to move in step by step manner so that no port is only partially opened and partially closed. As shown in Fig. 4, the side 92 of the housing is provided with a series of recesses 108 into which a ball 110 indicated in dotted outline may drop therewith. The ball is mounted in a cavity on the underside of the valve member and is carried around therewith when the latter rotates. The ball and the recesses are so located with respect to the inlet ports 90 that when the valve member moves to open or close another port the ball falls into a recess following complete opening or closing of the port and thereby resistingly checks further rotation of the valve member.

Raw gas is delivered to the valve control housing 82 by means of a delivery line or pipe which opens into the housing on the side opposite to the series of inlet ports 90. Preferably this gas is delivered at a substantially constant pressure, which pressure may be regulated by a control device generally indicated at 100. Such device includes the valve 102 connected by a valve stem 60 to a pressure responsive member such as the diaphragm 104. The diaphragm is responsive to differential pressures exerted against the opposite sides thereof. One side is exposed to the pressure of the raw gas admitted by valve 102 and delivered therefrom to the distributing device enclosed within the housing 82. The opposite side of the diaphragm is exposed to the pressure of air delivered thereto by the conduit 106 which as shown in Fig. 1 opens into the air duct 16 at some point between the fan 26 and the air heater 28. This air pressure falls as the temperature increases, thus the same falling pressure can be imparted to the raw gas due to the regulating action of the control device 100. This air pressure is relatively constant. If the pressure

of the raw gas flowing through the control device 100 should fall, such as by the opening of more inlet ports 90; the change in the differential pressures exerted on the diaphragm will cause the valve 102 to open further and admit more raw gas to distributing control device in the housing 82. Should the pressure of the raw gas increase beyond the desired amount, the change in the differential pressure will lift the diaphragm and cause the valve 102 to move toward closed position thereby reducing the amount of raw gas supplied to the housing 82.

The air heater portion of the apparatus enclosed within the casing 28 forms a separate installable unit of the air circulating duct system. As previously mentioned it may be installed on the discharge side of air blower and function as a blow-through type of air heater, or it may be installed on the inlet side of the system's air moving fan. To facilitate installation and removal as a separate unit, the casing 28 of the air heater is provided with outwardly extending radial flanges 112-112 at the opposite ends thereof. Each flange is provided with a series of circumferentially spaced openings or holes 114 through which fastening means such as bolts or rivets may extend to secure the unit between comparable end portions of the sections making up the duct system 16. The air heater may thus be separately manufactured and installed without difficulty wherever it may be desired in the air circulating system.

The operation of the system is generally understood from the previous description. When the system is first started up, the air in the chamber, oven or space to be heated is relatively cold and heavy and normally without any control of the capacity of the air heater, a considerable load will be imposed on the motor driving the air moving fan 26. However, the control motor 78 of the present system in response to the relatively cool temperature of the treatment chamber will have shifted the annular plate 68 until the openings 66 for the annular passage 45 are substantially closed thereby reducing the volume of air capable of passing through the air heater. Moreover, the plug 46 may be adjusted by the control 62 to substantially its closed position in the sleeve 48. This will reduce the load on the fan motor thereby enabling a motor of a lower horse power rating to be used. At the same time the control motor 88 in response to the temperature in the treatment chamber will have moved the valve member 84 in a counterclockwise direction in Fig. 4 to substantially the maximum open position. As a result substantially all the burner units 30 will receive raw gas for operation. The combustible mixture flowing from all these burners will be ignited by the single continuously operated pilot burner and the air heater will be functioning at substantially its maximum heating effectiveness.

As the temperature rises in the treatment chamber or other space being heated by the system, the control motor 78 will function to rotate the annular plate 68 so that the openings 66 are progressively opened in proportion to the rise in temperature. More air is admitted into the air heater increasing the amount of air moving through the air heater. The conical plug 46 may be adjusted to open the passage through the innermost sleeve 48 thereby further increasing the air capacity of the air heater and providing an amount of secondary air approximately equal to that supplied by way of the annular passage 45.

As the temperature continues to rise the control motor 88 will function to rotate the valve member 84 in a clockwise direction in Fig. 4 toward its position successively cutting off the delivery of gas to the burners and thereby reducing in step by step manner the number of burners in operation.

If the controls are set to provide a limit to the rise in temperature in the heat treatment chamber, for example 450° F., as this temperature is approached the number of burners in operation will be reduced until the temperature levels off at this desired limit. The graph in Fig. 5 represents the operation of the system from a start in cold condition. If 450° F. is the desired temperature, the controls may be set so that the temperature curve begins to level off at this degree level. If it should go above as indicated in the graph, one or more burners will be cut off thus reducing the effectiveness of the air heater. This will cause the temperature of the air in the treatment chamber to fall and if it should go below the desired degree, one or more burners will be cut in. In actual practice, the temperature curve after approximating the desired limit will fluctuate slightly above and below the desired degree as shown in the graph and the cutting in or out of one burner by the valve member 84 will suffice to hold the temperature at substantially the desired level.

During the operation of the air heater, the raw gas delivered to the burners will be preheated as it passes through the coils 35 just prior to admission to the Venturi tubes. This will expand the volume of gas proportionately to the temperature of the air heated. The volume of gas delivered to the Venturi tubes therefor maintained proportionate to the volume of air flowing through Venturi tubes. Since the gas is admitted into the Venturi tubes at substantially their point of minimum diameter, the action of the air passing these inlet ports 34 induces a suction which obviates the necessity of maintaining the gas under high pressure. The gas need only be under a sufficient amount of pressure to feed it to the burners.

What I claim is:

1. An air heating apparatus comprising, in combination, a generally circular casing, a series 50 of gas burner units in the form of Venturi tubes arranged in the interior of the casing in a substantially circular relation around the axis of the casing, said Venturi tubes occupying less than the total cross sectional area of the casing so as to provide one or more air passages between the Venturi tubes for the uninterrupted flow of air through the casing, means for causing air to be heated to flow through the casing from one end to the other end thereof, said Venturi tubes having their axes extending substantially parallel to the axis of the casing so that a part of the air flowing therethrough is caused to flow through the Venturi tubes, means for delivering gas to each burner unit and causing the gas to enter 60 each Venturi tube at substantially the minimum cross sectional area thereof so that the gas mixes with the air flowing through the Venturi tubes, means responsive to the temperature of the air heated by said burner units for cutting off the operation of one or more of the burner units to prevent increase in the temperature of the air beyond the desired temperature level, valve means for one of said air passages adjustable to vary the amount of air flowing therethrough, 70 and means responsive to the temperature of the

air heated by said burner units for adjusting said valve means according to the temperature of the air.

2. An air heating apparatus comprising, in combination, a generally circular casing, a series of gas burner units in the form of Venturi tubes mounted in the interior of the casing in a substantially circular relation around the axis of the casing and in spaced relation to the inside surface of the casing to form an annular air passage therebetween, said Venturi tubes having their axes substantially parallel to the axis of the casing and their inlet and outlet openings in corresponding positions in the casing, means for causing air to be heated to flow through the casing at a relatively high velocity from one end to the other end thereof and causing part of the air to flow through the Venturi tubes and another part of the air to flow through the annular passage between the Venturi tubes and the inside surface of the casing, means for delivering raw gas to each burner unit and causing the gas to enter each Venturi tube substantially at the minimum cross sectional area thereof, means responsive to the temperature of the air heated by said burner units for cutting off the operation of one or more burner units to maintain the air at the desired temperature level, adjustable valve means controlling the amount of air flowing through said annular passage, and means responsive to the temperature of the air heated by said burner units for adjusting said valve means in accordance with the temperature of the air.

3. An air heating apparatus comprising, in combination, a generally circular casing, a series of gas burner units in the form of Venturi tubes substantially circularly arranged in the interior of the casing but in spaced relation to the axis of the casing and the inside wall of the casing so as to form an axial air passage and an annular air passage, said Venturi tubes having their respective passages extending substantially parallel to the axis of the casing, means for causing air to be heated to flow through the casing from one thereof to the other and to flow through said axial and annular passages and the passages of said Venturi tubes, means for separately delivering gas to each burner unit and causing it to enter the passage of each Venturi tube at substantially the minimum diameter thereof, means responsive to the temperature of the air heated by the apparatus for varying the number of burner units in operation in order to maintain the air at the desired temperature level, adjustable valve means for said annular passage and a separate adjustable valve means for said axial passage adapted upon adjustment to vary the amount of air flowing therethrough, and means responsive to the temperature of the air heated by the apparatus for adjusting at least one of said valve means so as to vary the amount of air flowing through the passage controlled thereby in direct proportion to the temperature of the air.

4. An air heating apparatus for installation in a circulatory air system comprising, in combination, a generally circular casing having means on the opposite ends thereof for securing the same in the system, a plurality of burner units in the form of Venturi tubes arranged in a circular series in the interior of the casing in spaced relation to the axis thereof and the inner surface thereof to form an axial air passage and an annular air passage therebetween,

said Venturi tubes being opened ended and having their respective passages extending substantially parallel to the axis of the casing, a gas delivery pipe for each burner unit adapted to communicate with an outside source of gas and opening into the Venturi tube passage of its burner unit at substantially the minimum cross sectional area thereof, each gas delivery pipe being coiled one or more times about its burner unit prior to opening into the Venturi passage thereof, adjustable valve means for each of said axial and annular passages, and means for controlling the adjustment of said valve means in order to vary the air capacity of the heating apparatus.

5. An air heating unit adapted to be installed in a duct of an air circulating system comprising, in combination, a generally circular casing having means on the opposite ends thereof for securing the same to the open ends of two separated sections of an air duct, a pair of sleeves of different diameters mounted in the casing concentric with the axis thereof and forming an axial air passage through the inner sleeve and an annular air passage between the outer sleeve and the casing, a plurality of gas burner units arranged in circularly spaced apart relationship in the area between said sleeves, each burner unit having an open ended Venturi passage extended substantially parallel with the axis of the casing, a gas delivery pipe for each burner unit adapted to communicate with an outside source of gas and having its discharge end opening into the Venturi passage of its respective burner unit at substantially the minimum diameter thereof, each gas delivery pipe being coiled one or more turns about its respective burner unit for preheating the gas prior to discharge into the Venturi passage, valve control means for varying the amount of air adapted to be passed through said annular passage, valve control means for varying the amount of air adapted to be passed through said axial passage, and control means operable from outside of said casing for adjusting said two valve means.

6. An air heating apparatus comprising, in combination, an elongated generally circular casing, a series of gas burner units in the form of Venturi tubes shorter in length than the length of the casing, means mounting the Venturi tubes in the interior of the casing in spaced relation to the opposite ends thereof and with the axes of the Venturi tubes extending parallel to the axis of the casing and their inlet and outlet openings in corresponding positions in the casing, said mounting means further disposing the Venturi tubes in spaced relation to the inside surface of the casing to form an annular air passage therebetween, means for flowing air to be heated through the casing at a relatively high velocity from one end to the other end of the casing and causing a part of the air to flow through the Venturi tubes and another part of the air to flow through the annular passage between the Venturi tubes and the inside surface of the casing, means for delivering gas to each burner unit and causing the gas to enter each Venturi tube substantially at the minimum cross sectional area thereof, and valve means in said annular passage controllable from outside of the casing for varying the volume of air flowing through the passage.

7. An air heating apparatus comprising, in combination, a generally circular elongated casing, a plurality of gas burner units in the form of open ended Venturi tubes shorter in length than

11

the length of the casing, means mounting the Venturi tubes in the interior of the casing in a circular series of less radius than the casing and forming a central passage on the axis of the casing and an annular passage between the Venturi tubes and the inner surface of the casing, said Venturi tubes being mounted in the same plane in the casing in spaced relation to the opposite ends of the casing and with their axes extending substantially parallel to the axis of the casing and with their inlet and outlet openings in corresponding positions in the casing, means for flowing air to be heated through the casing from one end to the other end thereof and causing a portion of the air to flow through the Venturi tubes and portions of the air to flow through the central and annular passages on either side of the Venturi tubes, means for delivering gas to each burner unit from outside of the casing and causing the gas to enter each Venturi tube substantially at the minimum cross sectional area thereof, and separate adjustable valve means in said annular passage and in said central passage for varying the volume of air flowing therethrough.

8. In a substantially closed circulatory air heating system including as parts thereof a chamber to be heated and a conduit opening at its opposite ends into communication with spaced areas of the chamber, a section of the conduit forming an air heater and provided in the interior thereof with a plurality of open ended tubular gas burners having their axes extending parallel to the axis of the section and occupying an area less than the total cross sectional area of the section to provide for the flow of air therearound, means for moving air through the system in one direction and causing the air passing through the air heater to divide and flow both through and around the gas burners, means for progressively increasing or decreasing the number of the gas burners in operation, and means responsive to the temperature of the air in said chamber for governing the action of said second mentioned means.

9. In a substantially closed circulatory air heating system including as parts of the circulatory system a chamber to be heated and a conduit opening at its opposite ends into communication with spaced areas of the chamber, a section of said conduit forming an air heater and having a plurality of open ended tubular gas burner units mounted in the interior of the section and arranged in a group spaced radially inwardly of the surrounding wall portion of the section to form an annularly shaped air passage therebetween, an air impelling device adjacent to one end of the air heater operable to move air through said section and through said burner units and through said annular passage, means for delivering gas to said burner units from an outside source of supply to mix with the air flowing therethrough to form a combustible mixture, an adjustable valve in said annular passage for varying the volume of air flowing therethrough, means responsive to the temperature of the air in said chamber for varying the number of burners in operation to maintain the air at the desired temperature, and separate means responsive to the temperature of the air in the chamber for adjusting said valve.

10. An air heating apparatus comprising, in combination, a generally circular casing, a plurality of open ended tubular gas burner units in the interior of the casing having their axes extending substantially parallel to the axis of the

12

casing and arranged in a group spaced radially inwardly on all sides thereof from the surrounding wall portion of the casing to form an annularly shaped air passage therebetween, means for flowing air to be heated through the casing to thereby cause a part of such air to flow through the burner units and another part of such air to flow through the annular passage, means for delivering gas to each burner unit to form a combustible mixture with the air flowing therethrough, a pair of annularly shaped plates disposed in said annular air passage in juxtaposition to one another, said plates each having a series of similarly shaped apertures spaced apart from one another approximately their respective circumferential dimensions, and means operable from outside of the casing for circularly adjusting one of said plates relative to the other plate from a position in which the apertures of the plate substantially register with one another to a position in which the apertures are substantially out of registration with one another in order to vary the volume of air flowing through the annular passage.

11. An air heating apparatus comprising, in combination, a generally circular casing, a pair of open ended sleeves of different diameters disposed inside of the casing in co-axial relationship to one another and to the axis of the casing, said sleeves cooperating with the casing to form an annularly shaped air passage between the larger diameter sleeve and the casing and a central passage through the smaller diameter sleeve, a plurality of tubular burner units mounted in the space between said sleeves in circularly spaced apart relationship around the axis of the casing and having their respective axes extending parallel to the axis of the casing, means for delivering gas from a source of supply outside of the casing to each burner unit for mixture with the air therewithin, an air impelling device at one end of the casing operable to force air under relatively high velocity through the casing and through said burner units and said annular and central passages, and means for adjusting the cross section areas of said annular and central passages to vary the volume of air flowing therethrough.

12. In a gas-fired air heating system, the method of operating the system which comprises continuously circulating the air to be heated in a moving stream through the system, causing the air stream of the system to flow through a combustion zone, introducing raw gas into the combustion zone at a plurality of points separated from one another transversely of the air stream flowing therethrough, utilizing the air in the air stream as the sole source of primary and secondary air for the combustible mixture by dividing the stream adjacent to each point into an inner core of primary air for immediate mixture with the raw gas introduced at that point and into an outer layer of secondary air for later mixture with the gas and primary air further along the stream, varying the volume of the air stream passing through the combustion zone in direct proportion to the temperature of the air stream, and varying the amount of raw gas introduced into the combustion zone in inverse proportion to the temperature of the air stream.

13. In a circulatory air heating system including a combustion zone in which the air in the system is heated and a chamber which is heated by the air in the system, the method of operating the system which comprises continuously

moving an air stream under forced draft through the system in one direction, introducing fuel from an outside source of supply into the combustion zone, utilizing the air stream of the system flowing through the combustion zone as the sole source of air for forming a combustible mixture with the fuel introduced into the combustion zone, varying the amount of fuel delivered to the combustion zone in inverse proportion to the temperature of the air in the chamber, and varying the volume of air flowing through the combustion zone in direct proportion to the temperature of the air in the chamber.

14. In a circulatory air heating system including a chamber to be heated by air and a combustion zone for heating the air, the method of operating the system which comprises continuously circulating an air stream under forced draft through the system in one direction, introducing a gaseous fuel from an outside source of supply into the combustion zone, utilizing the air stream of the system flowing through the combustion zone as the sole source of air for forming a combustible mixture with the gaseous fuel thus introduced, controlling the amount of gaseous fuel delivered to the combustion zone in inverse proportion to the temperature of the air in the chamber.

ber, and controlling the pressure of the gaseous fuel thus introduced in accordance with the pressure of the air stream flowing through the combustion zone.
